United States Patent Office

Des. 213,902
Patented Apr. 22, 1969

213,902

DESK LAMP

Henry P. Muller, Rego Park, N.Y., assignor to Lightolier
Incorporated, Jersey City, N.J., a corporation of New York

Filed Apr. 13, 1967, Ser. No. 6,679

Term of patent 7 years

Int. Cl. D26—02

U.S. Cl. D48—20

FIG. 1

FIG. 2

FIG. 3

FIG. 4

FIG. 5

FIG. 1 is a side elevational view of the desk lamp showing my new design;

FIG. 2 is a top plan view thereof;

FIG. 3 is a front elevational view thereof;

FIG. 4 is a rear elevational view thereof; and

FIG. 5 is a bottom elevational view thereof.

The dominant features of my design reside in the portions shown in full lines.

I claim:

The ornamental design for a desk lamp, substantially as shown and described.
